NARROW SLIT DITCHER

Walter P. Winsett, Memphis, Tenn., assignor to Marion H. Winsett and William E. Ford, both of Houston, Tex., fractional part interest to each

Filed June 2, 1971, Ser. No. 149,406

Term of patent 14 years

Int. Cl. D15—04

U.S. Cl. D39—1 B

FIG. 1 is an isometric view showing the top, front and left side of a narrow slit ditcher, showing my new design;

FIG. 2 is a side elevational view of the right side thereof; and

FIG. 3 is a rear elevational view thereof. The bottom view, not shown, appearing as a flat plate base, with the undersides of the four wheels being disposed to appear in correspondence with the wheels of the views hereinabove described.

I claim:

The ornamental design for narrow slit ditcher, as shown and described.
